UNITED STATES PATENT OFFICE.

JOHN LEONARD HOLMAN AND ARTHUR TREVE HOLMAN, OF CAMBORNE, ENGLAND,
ASSIGNORS TO HOLMAN BROTHERS LIMITED, OF CAMBORNE, CORNWALL, ENGLAND, A BRITISH COMPANY.

FLUID-OPERATED RECIPROCATING MACHINE TOOL.

Original application filed May 9, 1925, Serial No. 29,108, and in Great Britain February 24, 1925.

Divided and this application filed July 13, 1926. Serial No. 122,181.

This invention relates to fluid-operated reciprocating machine-tools, such for example as pneumatic hammers for riveting, chipping, caulking and such like operations, 5 of the kind wherein a handle member is detachably attached to a body portion containing the working cylinder for the reciprocating piston, which cylinder extends into a recess in the handle member, and the invention has particular reference to the construction and arrangement of the handle of the 10 tool, one object being to enable the handle member to be manufactured at a low cost, and another being to provide an improved joint 15 between the handle member and body portion.

According to the invention these objects are attained by providing that the said recess constitutes by itself, or by means only 20 of a liner within it, a portion of the working cylinder, and the said fluid-tight joint is constituted by a joint ring which is malleable or compressible interposed between the opposed end faces of the handle member and body 25 portion, whereby a close and fluid-tight joint between these parts can be obtained even if the opposed end faces are of such a nature that when placed directly face-to-face a fluid-tight joint would not result.

In order that the invention may be more clearly understood one preferred construction of riveting hammer will now be described by way of example only with the aid of the accompanying drawings, in which—

Figure 1 is a longitudinal central section through the hammer;

Figure 2 is a section on the line 2—2 of Figure 1; and

Figure 3 illustrates partly in outside elevation and partly in section a modification 40 of the invention.

Like reference numerals indicate like parts in the several figures.

Referring first of all to Figures 1 and 2 45 the handle 10 is provided with the usual trigger-controlled throttle valve 11, the trigger of which is shown at 12. The valve 11 admits driving fluid, for example, compressed air, from the main supply conduit 13 by way of a port 14 to an annular recess 15 formed in the body of the handle. A liner 16 constitutes the inner wall of the re-

cess 15 and also serves as an extension of the working cylinder 24 of the tool.

The annular recess 15 communicates with 55 a pair of ports 17 which coincide with similar ports in a joint ring 18 and in the cylinder casing 19.

The joint ring is preferably composed of fibre or other packing or jointing material 60 which will enable a close and fluid-tight joint to be obtained between it and the handle on one side and the cylinder casing 19 on the other side. The material may be such as to be slightly compressible so that the parts on 65 the other side can become slightly embedded in it. The construction, arrangement and operation of other parts of the tool are described in co-pending application Serial No. 29,108, filed 9th May, 1925, from which this 70 application has been divided out, and as, except for the handle and joint ring, the other portions of the tool form no part of the present invention they will not be described herein except to point out that in the joint ring 75 18 there is a port 118 communicating as shown, directly with the end of the valve chamber 22 and with another port 38 by which driving fluid is led into the rear end of the working cylinder 24.

In a modified form of the invention as illustrated in Figure 3, the handle 10 is of hooked or open form and the fluid supply is taken direct from a passage 140 in the handle through the port in the joint ring 18 to the 85 valve chamber 22 without passing through an annular passage round a cylinder extension such as 116. In this case the extension 116 is not bushed as in the example illustrated in Figure 1.

Referring to the joint ring it is to be observed that it may be of any preferred material not necessarily fibre as referred to hereinbefore. For instance it may be composed of an asbestos graphite composition or it may be formed of lead or even of other material which is not necessarily compressible.

The provision of such a joint ring has a considerable advantage in that the machining of the faces of the two parts between 100 which it is disposed need not be carried out with such accuracy as would be necessary if the two parts were held together face to face so as to give the required fluid-tightness to

the joint between them. Also, when the joint ring becomes damaged or worn so that it is no longer efficiently serviceable, it may be readily replaced, and its replacement is a matter of small expense only. Another advantage is that the faces of the joint ring, when the latter is made of material into which the parts can be somewhat embedded, require no machining and the joint ring can be stamped, moulded or otherwise formed according to the nature of the material employed.

We claim:

15. A fluid-operated reciprocating machine-tool comprising in combination a body portion containing one part of a working cylinder for a reciprocating piston, a handle member detachably attached to said body portion and having a recess, a liner in the latter dividing the recess into an annular fluid-supply passage, and a chamber that is surrounded by said passage and constitutes another part of the working cylinder, a valve chamber in said body portion, a reciprocating valve in said chamber, and a joint ring composed of yielding material interposed between opposed end faces of said body portion and handle member and constituting one end wall of the valve chamber, substantially as described.
20. In testimony whereof we have signed our names to this specification.
25. JOHN LEONARD HOLMAN.
ARTHUR TREVE HOLMAN.

portion and handle member, which joint ring has ports for permitting communication between said parts of the working cylinder, and between the valve chest and the working cylinder, and between the said annular passage and the valve chest, substantially as described.

2. A fluid-operated reciprocating machine-tool comprising in combination a body portion containing one part of a working cylinder for a reciprocating piston, a handle member detachably attached to said body portion and having a recess, a liner in the latter dividing the recess into an annular fluid-supply passage, and a chamber that is surrounded by said passage and constitutes another part of the working cylinder, a valve chamber in said body portion, a reciprocating valve in said chamber, and a joint ring composed of yielding material interposed between opposed end faces of said body portion and handle member and constituting one end wall of the valve chamber, substantially as described.

In testimony whereof we have signed our names to this specification.

JOHN LEONARD HOLMAN.
ARTHUR TREVE HOLMAN.
